CONTAINER

John M. Hothersall, Brooklyn, N. Y., assignor to
 American Can Company, New York, N. Y., a
 corporation of New Jersey

Application August 2, 1934, Serial No. 738,152

5 Claims. (Cl. 206—16)

The present invention relates to containers for flexible safety razor blades and has particular reference to one piece compartment containers in which means are provided for disposing of 5 blades which have been used.

An object of the invention is the provision of a container for safety razor blades which is formed from a single piece of material having a portion which is set off as a partition for dividing 10 the container into two compartments, one of which is utilized for holding unused blades which are adapted to be withdrawn for use from an open end of the compartment while the other compartment is adapted to receive used blades 15 and to hold them captive against escape.

Another object is the provision in such a container of a compartment dividing partition having spring elements associated therewith which are self-adjusting to hold one or more than one 20 blade in either compartment.

Another object is the provision of an inexpensive container which is adapted to hold a supply of unused blades, which provides a place of disposal for used blades and which may be 25 readily discarded after use without danger of the used blades becoming separated from the container and causing damage.

Numerous other objects and advantages of the invention will be apparent as it is better understood from the following description, which, 30 taken in connection with the accompanying drawing, discloses a preferred embodiment thereof.

Referring to the drawing:

Figure 1 is a perspective view of a container embodying the instant invention;

Fig. 2 is a perspective view of the container inverted showing the bottom, side and end walls which are not shown in Fig. 1;

Fig. 3 is a plan view of a blank from which the container is formed;

Fig. 4 is an enlarged longitudinal section taken substantially through the center of the container; and

Fig. 5 is a transverse section taken substantially along the line 5—5 in Fig. 4.

As a preferred embodiment of the invention the drawing illustrates a rectangular shaped flat container or package which is divided into upper 50 and lower compartments by a partition formed as an integral part of the container. It is preferably formed from a single blank 12 (Fig. 3) of sheet metal which is bent along predetermined lines to provide the various necessary walls and wall sections.

The container when formed from the blank 12 comprises a bottom wall 13 which merges into a vertical side wall 14 and a wall section 15, these being formed by bending the blank 12 up and at right angles to the bottom wall indicated by parallel dotted lines *a*, *b* in Fig. 3. A horizontal top wall 16 connects with the side wall 14 along one longitudinal corner and is formed by bending the blank at right angles to the side wall indicated by dotted line *c*. 5

The side wall section 15 extends approximately one third of the distance between the bottom wall 13 and the top wall 16 and is bent inwardly 10 at right angles as indicated by dotted line *d*. This bending sets off and disposes partition 17 15 inside of the container dividing it into an upper compartment 18 and a lower compartment 19 for a purpose hereinafter explained.

A side wall section 21 cooperates with the side wall section 15 to provide a side wall of the same 20 height as the wall 14. Wall section 21 is formed by bending the blank at right angles to the top wall 16 along line *e*. The wall part 21 is supported on top of the partition 17 and in alignment with the wall 15. 25

The bottom edge of the wall 21 is bent inwardly at *f* forming a flange 22. Flange 22 may be secured to the partition in any suitable manner as by soldering or welding or if desired it may rest loosely thereon if there is sufficient stiffness 30 of the structure to hold the parts together.

The container is completely formed by bending the end portions of the blank into position. One end of the container is entirely closed by a two piece inclosure comprising a wall section 35 23 which extends up from the bottom wall 13 and a wall section 24 which depends from the top wall 16. Walls 23, 24 are brought into co-operating position by bending the blank along lines *g* and *h*, respectively. 40

The other or forward end of the container is only partially closed by a wall 25 which extends up from the bottom wall 13. This wall is brought into the proper position by bending the blank along line *j*. The wall 25 extends as far as the 45 partition 17 and overlaps its forward edge. This substantially covers the end of the lower compartment but does not extend in the front of the upper compartment.

The upper compartment 18 is utilized for holding a supply of unused blades 28 (Figs. 4 and 5) which are confined between the top wall 16 and the partition 17. These blades may be wrapped in paper in the customary commercial manner. The forward end of the compartment is open 55

for removal of the blades and the top wall 16 adjacent this open end is notched out as at 29 to facilitate this removal.

5 The blades are held within the compartment 18 and against accidental removal by spring fingers 31. There are two of these fingers and they are struck out from the partition 17 adjacent its longitudinal edges. The fingers project into the compartment and engage against the bottom 10 of the lowermost blade 28 in the stack and press all the blades that are in that compartment toward the top wall 16 thereby frictionally holding them in.

15 The lower compartment 19 is utilized as a place of disposal for used blades. This compartment is substantially enclosed, the only means of entrance for the blades being adjacent the end wall 25 at the intersection of its top edge and the partition 17. The top edge of end wall 25 is 20 arched as at 32 (Figs. 1, 3, and 5) forming openings at the sides of the arch into which a corner of the blade may be inserted. Using the blade as a lever with the arch as a fulcrum, the partition 17 is sprung up enough to permit the blade 25 to pass between it and the curved edge 32.

When fully inserted in the compartment the blade is trapped and cannot escape as the partition springs back into its original position as soon as the blade clears the curved edge 32. At 30 the same time the blade within the compartment is engaged by a spring finger 33 which is similar to the fingers 31 and which like them is struck out from the partition wall being between the fingers 31. This finger 33 presses the blades 35 against the bottom wall 13 and holds it below the entrance opening and out of the way of subsequently inserted blades.

In this manner the used blades may be kept 40 separate from the unused blades while the container is in use or as long as there are unused blades. When these are exhausted the container is discarded without danger of the used blades becoming separated from their confining compartment.

45 It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

55 1. A one piece sheet metal package for razor blades, comprising a sheet metal blank bent to form top and bottom walls and opposite pairs of vertical walls all integrally connected together, one edge of the blank terminating intermediate 60 a vertical wall, another portion of said blank constituting the remaining part of said last mentioned vertical wall and abutting against the aforesaid terminal edge, said blank portion being bent sharply inwardly at the point of abutment to constitute a partition member within 65 said package spaced from the top and bottom walls thereof and dividing the interior of the package into separate superposed compartments for new and used razor blades respectively.

70 2. A one piece sheet metal package for razor blades, comprising a sheet metal blank bent to form top and bottom walls and side and end

walls all integrally connected together, one edge of the blank terminating intermediate one of the side walls, another portion of said blank constituting the remaining part of said last mentioned side wall and abutting against the aforesaid 5 terminal edge, said blank portion being bent sharply inwardly at the point of abutment to constitute a resilient partition member within said package spaced from the top and bottom walls thereof and dividing the interior of the 10 package into separate superposed compartments for new and used razor blades respectively.

3. A one piece sheet metal package for razor blades, comprising a sheet metal blank bent to form top and bottom walls and opposite pairs of vertical walls all integrally connected together, one edge of the blank terminating intermediate a vertical wall, another portion of said blank constituting the remaining part of said last mentioned vertical wall and abutting against 20 the aforesaid terminal edge, said blank portion being bent sharply inwardly at the point of abutment to constitute a partition member within said package spaced from the top and bottom walls thereof and dividing the interior 25 of the package into separate superposed compartments for new and used razor blades respectively, one of said walls having a curved edge cooperating with an edge of said partition member to provide an opening through which a 30 razor blade may be inserted into the package, said curved edge confining said inserted blade within the package.

4. A one piece sheet metal package for razor blades, comprising a sheet metal blank bent to 35 form top and bottom walls and side and end walls all integrally connected together, one edge of the blank terminating intermediate one of the side walls, another portion of said blank constituting the remaining part of said last mentioned 40 side wall and abutting against the aforesaid terminal edge, said blank portion being bent sharply inwardly at the point of abutment to constitute a resilient partition member within said package spaced from the top and bottom walls 45 thereof and dividing the interior of the package into separate superposed compartments for new and used razor blades respectively, and integral- 50 ly formed resilient members struck from and extending out of the plane of said partition member for yieldably confining razor blades in a said compartment.

5. A one piece sheet metal package for razor blades, comprising a sheet metal blank bent to form top and bottom walls and opposite pairs 55 of vertical walls all integrally connected together, one edge of the blank terminating intermediate a vertical wall, another portion of said blank constituting the remaining part of said last mentioned vertical wall and abutting 60 against the aforesaid terminal edge, said blank portion being bent sharply inwardly at the point of abutment to constitute a partition member within said package spaced from the top and bottom walls thereof and dividing the interior 65 of the package into separate superposed compartments for new and used razor blades respectively, and resilient members extending out of the plane of said partition member for yieldably confining razor blades in a said compartment. 70
